UNITED STATES PATENT OFFICE.

JAMES H. DICKSON, OF PHILADELPHIA, PENNSYLVANIA.

ENGRAVER'S TURN-TABLE OR HOLDER.

SPECIFICATION forming part of Letters Patent No. 340,429, dated April 20, 1886.

Application filed April 11, 1885. Serial No. 161,923. (No model.)

To all whom it may concern:

Be it known that I, JAMES H. DICKSON, a citizen of the United States, residing in the city and county of Philadelphia, State of Pennsylvania, have invented a new and useful Improvement in Engravers' Turn-Tables, which improvement is fully set forth in the following specification and accompanying drawings, in which—

10 Figure 1 represents a top or plan view of an engraver's turn-table embodying my invention, a portion of the same being broken away. Fig. 2 represents a vertical section thereof.

15 Similar letters of reference indicate corresponding parts in the two figures.

My invention consists of an engraver's turn-table which may be set at various angles, and is adapted for holding different kinds of articles to be engraved, as will be hereinafter fully set forth.

20 Referring to the drawings, A represents a table on which are supported two blocks or slides, B, to the under side of which are secured, by means of screws C, the ears D D, which latter may be of dovetail or tapering form, it being noticed that said blocks or slides B are on opposite sides of the table.

25 F represents a right-and-left-threaded screw, which is swiveled to the standard of the table and fitted to the ears D D, whereby by the operation of said screw the blocks B may be moved simultaneously toward or from each other, as desired. A portion of the sides of

30 each block B is right-lined, as at G, and the remaining portion is scalloped and grooved, as at G', by which provision the blocks are adapted for holding different articles or for different kinds of work, it being noticed that

35 the blocks may be rotated on the screws C, so as to bring the proper part around to the work.

40 The upper faces of the blocks are also formed with a series of openings to receive pins H, which are shouldered, the same being adapted 45 to be fitted in either of said openings, and owing to their shoulders to be employed for various kinds of work, it being seen that when the blocks or pins, or both, are adjusted they are caused to take firm hold of the article to

50 be engraved by clamping action due to the

screw F, and when the work is accomplished the article may be readily released by properly rotating the screw F, in which case the blocks recede and separate. A depression, H', is also formed on the face of the block, or in each block, forming a seat or rest for holding rings, &c., to be engraved. The standard J of the table is freely fitted in a socket, J', so that the table may rotate thereon, the said socket having at its lower end a flange, K, of inverted cup shape, or somewhat hemispherical, and this is fitted within a socket, L, of corresponding shape, forming a ball-and-socket joint, the socket being attached to the base of the table. Within said base is a clamping-bar, 60 M, which may be raised and lowered, and when raised is adapted to come in contact with a projection depending centrally from the ball or flange K. One end of said bar is rested on a piece, N, as a fulcrum, and has fitted to its other end a screw, P, by which provision said bar may be raised and lowered. When the bar is clamped against the projection of the ball or flange K, it forces said flange against the socket L, and thus retains the said flange, 65 and consequently the table A, in whatever position it may be placed, it being evident that owing to the ball-and-socket joint K L the table may be set at any desired angle for the purpose of the engraver, and when once 70 thus set or adjusted it is retained in position by the clamp-bar M. When the said bar is lowered by the screw P, it relieves the ball K, and thus permits the angular adjustment of the table, as desired. 75

Having thus described my invention, what I claim as new, and desire to secure by Letters Patent, is—

1. The rotary slotted table A, provided with adjustable sliding blocks B, having recesses 90 on the upper face, and provided with pins H, having shouldered portions, in combination with the right-and-left-threaded screw F, swiveled in the standard J and working in the ears D, substantially as and for the purpose 95 set forth.

2. The adjustable blocks B, having right-line portions G and curved scallops G' on the rim thereof, in combination with the rotary table A and right-and-left-threaded screw F, 100

the said blocks B having ears D, which are secured to the said blocks by means of screws, whereby the said blocks may be adjusted so as to present different portions of their rims to each other, substantially as and for the purpose set forth.

3. An engraver's turn-table composed of a rotary table with sliding blocks, a right-and-left-threaded screw, a standard in which said screw is journaled, a base, a ball-and-socket joint connecting the standard with the base, and a clamping device, said parts being combined and operating substantially as and for the purpose set forth.

5 4. An engraver's turn-table composed of a rotary table with blocks having both a lateral

and a rotary adjustment and provided with pins adapted to be inserted in recesses in said blocks, a right-and-left-threaded screw, a standard for said table having a flange at the 20 lower end, a socket secured to the base embracing said flange, and a clamping device bearing on said flange, substantially as and for the purpose set forth.

5. The table A, having a standard, J, in 25 combination with the flange K, socket L, secured to the base of the table, lever-bar m, and screw P, substantially as described.

JAMES H. DICKSON.
